FIG. 1

INVENTOR.
W.T. HATMAKER.

BY
Edward Reed
ATTORNEY.

UNITED STATES PATENT OFFICE.

WILLIAM T. HATMAKER, OF DAYTON, OHIO, ASSIGNOR TO THE PROTECTO PUMP COMPANY, OF DAYTON, OHIO, A CORPORATION OF OHIO.

DESIGN FOR AN OIL-DISPENSING DEVICE.

60,189.

Specification for Design.

Patented Jan. 10, 1922.

Application filed July 19, 1920. Serial No. 397,503. Term of patent 14 years.

To all whom it may concern:

Be it known that I, WILLIAM T. HATMAKER, a citizen of the United States, residing at Dayton, in the county of Montgomery and State of Ohio, have invented a new, original, and ornamental Design for an Oil-Dispensing Device, of which the following is a specification, reference being had to

the accompanying drawing, forming part thereof.

The figure is an elevation of an oil dispensing device showing my new design.

I claim:

The ornamental design for an oil dispensing device as shown.

WILLIAM T. HATMAKER.
